SCOREBOARD

Robert J. Roston, William O. Boss, and Arnold R. Holt,
New York, N.Y., assignors to City of Anaheim, a municipal corporation of California

Filed Oct. 3, 1966, Ser. No. 4,128

Term of patent 14 years

(Cl. D96—12)

FIG. 1 is a front perspective view taken from the left side of a scoreboard showing our new design; and

FIG. 2 is a rear perspective view taken from the right side thereof, the bottom of the center board being plain.

We claim:

The ornamental design for a scoreboard, substantially as shown and described.
